The ornamental design for a fastener for papers, as shown and described.

DESCRIPTION

FIG. 1 is an exploded front elevational view of the fastener for papers showing my new design;

FIG. 2 is an exploded side elevational view thereof, the opposite side view being a mirror image;

FIG. 3 is an exploded rear elevational view thereof;

FIG. 4 is a front elevational view showing the fastener in its assembled state.

FIG. 5 is a view corresponding to FIG. 4 and showing the cooperation between the tubular legs of the fastener and the securing piece.

FIG. 6 is a top plan view thereof; and,

FIG. 7 is a bottom plan view thereof.
